2 Sheets-Sheet 2

UNITED STATES PATENT OFFICE

MICHAEL LEONARD, OF ROLETTE, NORTH DAKOTA

CHIMNEY HEATER

Application filed July 16, 1932. Serial No. 622,949.

My invention relates to a heater designed to receive its heat from a chimney, stack, smoke pipe, or the like.

In accordance with my invention, I provide a heater which may be installed as a unit in a chimney when the chimney is being constructed. The heater embodies a frame which is strong, and durable, and serves to support the upper portion of the chimney, and is intended to be permanent. The heater embodies tubes or flues which may be removable for the purpose of replacement. The tubes or flues may be surrounded by a jacket, which is preferably removable. The jacket serves to cause a circulation of cool air from the room into the jacket, and from within the jacket into the room, and also serves to prevent the hands from coming in direct contact with the flues. The heater is installed in a chimney above the fireplace, such as in the second story of a building, and will efficiently utilize the heat contained in the smoke and products of combustion for heating the room in which the device is arranged.

In the accompanying drawings, forming a part of this specification, and in which like numerals are employed to designate like parts throughout the same,

Figure 1 is a side elevation of a heater embodying my invention, showing the same in place, parts being broken away for the purpose of illustration,

Figure 2 is a perspective view of the heater, the casing being removed,

Figure 3 is a vertical longitudinal section taken on line 3—3 of Figure 4,

Figure 4 is a horizontal section taken on line 4—4 of Figure 3,

Figure 5 is a perspective view of the casing or shield,

Figure 6 is a detail section taken on line 6—6 of Figure 5,

Figure 7 is a fragmentary side elevation of the corner of the shield or casing,

Figure 8 is a side elevation of one guard plate, and

Figure 9 is a similar view of another guard plate.

In the drawings, wherein for the purpose of illustration is shown a preferred embodiment

of my invention, the numeral 10 designates a building or dwelling as a whole, having a first floor 11 and a second floor 12. The numeral 13 designates a brick chimney as a whole, comprising a fireplace 14, arranged within the first floor 11 and a lower chimney section 15 and an upper chimney section 16. My heater is designated as a whole, by the numeral 17, and is arranged between the chimney sections 15 and 16, and supports the upper chimney section 16, as shown.

My heater comprises upper and lower boxes 18 and 19, formed of heavy gauge sheet metal, or the like. The box 18 has a bottom 20, and a top 21. The top 21 has a central opening 22, to register with the bore of the upper chimney section 16, the bricks of the upper chimney section resting upon the top 21 around the opening 22. In order that there may be no tendency for the top 21 to bend downwardly near the opening 22, I preferably provide spaced vertical struts 23, which are rigidly attached to the top 21 and bottom 20, around the marginal edge of the opening 22. The bottom 20 is provided with openings 24, four of which are shown for the purpose of illustration. The lower box or casing 19 includes a bottom 25 having a central opening 26 to register with the bore of the lower chimney section 15, this bottom resting upon the bricks constituting the walls of the chimney section 15. The box 19 includes a top 27 having openings 28 formed therein. Four of these openings 28 have been shown for the purpose of illustration, and these openings are in alignment with the openings 24. The openings 28 are surrounded by upstanding flanges 29. Reinforcing struts 30 are also arranged within the lower box 19, connecting the bottom 25 and top 27, to stiffen the structure.

The boxes 18 and 19 are shown as square in horizontal cross-section, for the purpose of illustration, and I employ four angle irons 31, arranged between the boxes 18 and 19, at their corners, and rigidly attached thereto by welding or the like. It is preferred that the outer surfaces of these angle irons be flush with the outer surfaces of the boxes. Diagonal brace rods 32 are preferably em-

ployed for connecting the angle irons, as shown.

- 5 Mounted within the openings 24 of the upper box are vertically adjustable tubular couplings 33, having flanges 34 at their upper ends. These couplings are designed to be permanent, and are formed of heavy gauge sheet metal. The numeral 35 designates a plurality of vertically arranged pipes or 10 flues, such as ordinary stove pipe sections, and these pipes have their lower ends mounted upon the tubular flanges 29, while their upper ends are inserted within the lower ends of the tubular couplings 33, which are 15 then moved downwardly to snugly receive the pipes 35. It is thus seen that when the pipes 35 become burnt or worn, they may be readily removed and new pipes substituted therefor.
- 20 The numeral 36 designates a shield as a whole, including plates 37, 38, 39 and 40. Each of the plates 37, 38, 39 and 40, is provided at one vertical edge with a flange 41, bent at a right angle with relation thereto, 25 and this flange has L-shaped slots 42 stamped therefrom, near its top and bottom. Each of the plates 37, 38, 39 and 40 is provided near its vertical edge, remote from the flange 41, with a pair of L-shaped slots 43. The 30 several angle irons 31 are provided upon corresponding faces with studs 46, arranged near their upper and lower ends.

The plate 38 may be applied to one side of the frame, then plate 39 arranged upon the next side, plate 40 upon the next side, and plate 37 upon the remaining sides. Each plate is moved downwardly so that the studs 46 will lock the plate to the angle iron. It 35 is thus seen that the several plates are removably mounted upon the frame.

The plates 37 to 40, inclusive, constituting the shield, terminate beneath the upper box 18, leaving a space 45 for the escape of heated air, and also are spaced from the head 19, 40 leaving a space 45', so that air may enter the lower wall of the shield.

It is to be understood that the form of my invention herewith shown and described, 45 is to be taken as the preferred example of the same, and that various changes in the shape, size and arrangement of parts may be resorted to without departing from the spirit of the invention, or the scope of the subjoined claims.

50 Having fully described my invention, what I claim is:

1. A heater to be arranged between chimney sections, comprising upper and lower

spaced boxes, a framework rigidly connecting the spaced boxes, pipes arranged between the spaced boxes, vertically adjustable tubular couplings connecting the upper ends of the pipes with the upper box, the arrangement being such that said pipes establish communication between the boxes. 70

2. A heater to be arranged between chimney sections or the like, comprising upper and lower spaced boxes, a frame rigidly connecting the spaced boxes, a vertically adjustable tubular coupling carried by the bottom of the upper box and extending below the same, a removable pipe arranged between the upper and lower boxes and having detachable engagement with the tubular coupling, and means whereby the pipe is detachably connected with the top of the lower box. 75

3. A heater to be arranged between chimney sections or the like, comprising spaced upper and lower polygonal boxes, bars arranged at the corners of the boxes and rigidly connecting them, a plurality of pipes arranged between the boxes and connecting them, the lower box having an opening in its bottom and the upper box having an opening in its top, and a shield surrounding the space between the boxes and secured to the bars. 80

4. A heater to be arranged between chimney sections or the like, comprising spaced upper and lower polygonal boxes, the lower box having an opening in its bottom and the upper box having an opening in its top, 100 pipes arranged between the boxes and in communication therewith, upstanding bars disposed at the corners of the boxes and rigidly secured thereto, said bars having studs, and a plurality of plates adapted to be mounted upon the bars, each plate having a flange at one vertical edge, said flange having L-shaped slots, each plate being provided near its opposite vertical edge with L-shaped slots, the arrangement being such that the several studs are adapted to extend through the slots in the plates and in the bars, and detachably lock the plates to the bars. 105

5. A heater to be arranged between chimney sections or the like, comprising spaced upper and lower polygonal boxes, pipe means connecting the boxes, a frame work rigidly connecting the boxes and a shield surrounding the frame work, said shield being spaced at its opposite ends from the boxes, affording 115 inlet and outlet air passages. 120

In testimony whereof, I affix my signature.
MICHAEL LEONARD.
